SPRING POCKET FILLING MACHINE

William K. McInerney and James M. McInerney,
Grand Rapids, Mich.

Application September 12, 1949, Serial No. 115,256

10 Claims. (Cl. 226—18)

1

This invention relates to a novel and rapid production machine for filling fabric pockets with coiled cushion springs. There has been previously filed in the Patent Office an application by J. L. McInerney, Serial No. 791,712, filing date of which is December 15, 1947, now Patent No. 2,647,671, dated August 4, 1953, for a spring loading machine. The present invention, using some of the structural features of such earlier filed machine, is concerned with novel structure and arrangements for greatly increasing production so that the fabric pockets may be filled, each with a coiled cushion spring, in succession one after the other, the pockets being conveyed or moved in succession to the filling or loading station, and a plurality of pockets simultaneously filled with the springs, the present machine also being adapted to receive the springs as they are delivered from a spring selecting and feeding machine, upon which we have recently filed application for patent, Serial No. 103,152 on July 5, 1949, now Patent No. 2,578,438, dated December 11, 1951.

It is an object and purpose of the present invention to provide a practical and operative machine for inserting in fabric pockets, a coiled spring in each pocket, very rapidly and expeditiously so that the machine operates substantially automatically as long as springs are supplied to it, and as long as the fabric pockets to receive the springs are attached to their conveyor for movement to the filling or loading station in a continuous succession of periodic movements, in each of which movements a plurality of the fabric pockets are moved to the filling station, all of them being supplied and filled each with a single spring in each cycle of operation of the machine. Many other objects and purposes, included in which is the structure for maintaining the springs in their pockets in compressed condition until they can be taken from the machine, for subsequent operations in which the springs are released to expand and turn to lie lengthwise of the pockets and the pockets closed at their open ends in which the springs are inserted, will be apparent and understood from the following description, and from drawings of an embodiment of the invention, which has been built and is in use, in which drawings

Fig. 1 is a plan view of the novel machine of our invention,

Fig. 2 is a front elevation of the machine,

Fig. 3 is an end elevation looking at the machine from the right in Fig. 1 and from the left in Fig. 2,

2

Fig. 4 is a fragmentary enlarged vertical section substantially on the plane of line 4—4 of Fig. 1, showing the coiled springs at the stage of operation of the machine wherein such springs are nearly compressed to their final stage of compression,

Fig. 5 is a section similar to Fig. 4, after the machine has been operated to completely compress the springs and are plunger ejected and moved into the pockets to receive them,

Fig. 6 is a fragmentary enlarged vertical section substantially on the plane of line 6—6 of Fig. 2,

Fig. 7 is a fragmentary rear elevation of the lower portion of the machine illustrating the mechanism used for operating the spring compressing means and the spring ejecting and pocket filling means,

Fig. 8 is a plan view and Fig. 9 is a longitudinal section through a periodic actuating mechanism for several conveyors which are driven in unison at intervals for moving the pockets and the spring receiving holders into position for receiving springs and moving them in compressed condition to the fabric pockets which receive them.

Like reference characters refer to like parts in the different figures of the drawings.

The frame of the machine includes at its front side an upper horizontal bar or rail 1, below and spaced from which is a lower elongated bar 2, supported above the floor by vertical posts 3. At the ends of the machine are cross bars 4 at right angles to the front wall 1 and connected therewith, which are connected to the outer ends of two bars 5 in alignment which (Fig. 1) extend toward each other, parallel to the bar 1, and join with spaced bars 6 located at right angles and extending rearwardly from the inner ends of the bars 5. Bars 6 are connected at their rear ends by bar 7 parallel to the bars 1 and 5 but back a distance therefrom. Other horizontal bars support and reinforce the frame. There are also other posts 3 at the junctures of the bars 5 and 6 and at the junctures of the bars 6 and 7. The horizontal bars 8 are a short distance above the floor and are connected with supporting posts 3, serving as supports, as hereafter described, for portions of the elements of the machine.

A horizontal table 9 extending the full length of the machine is located at the front of the machine above the upper ends of the front posts 3 as shown. At the rear edge of the table 9 an elongated guide 10 is secured, and back of it a second or narrower table or board 11 secured per-

3
manently in place. The guide 10 guides the upper run of a continuous conveying chain 12 which, at spaced distances in its length, is provided with outwardly extending sharpened pins 13 which in the upper run of the chain are located vertically with their pointed ends extending upwardly. Chain 12 is carried around sprocket or chain wheels 14 on shafts 15 which are suitably mounted to be supported by the lower horizontal frame bars 2 (Fig. 2) said shafts 15 being located adjacent either end of the machine. Other wheels 16 also are secured to the shaft 15 in front of the wheels 14, around which an endless chain 17 passes. The chain 12 at each end is extended upwardly over idle wheels 14a (Fig. 2) so that the upper run of the chain 12 is carried above and in the guide 10 therefor, the lower runs of both chains 12 and 17 are in the same horizontal plane, while the upper run of the chain 17 is in a plane between the upper and lower runs of the chain 12 (Fig. 2).

An electric motor 18 (Figs. 1 and 3) is located back of the machine and, through a belt 19 and reduction gearing within a gear box 20, drives a horizontal shaft 21 which extends to the front of the machine. At its front end (Fig. 2) it is equipped with a crank arm 22 to which one end of a connecting bar 23 is pivotally connected. A fixed bearing 24 near the floor of the machine carries a rock shaft 25 to which the lower end of the bar 26 is connected, the connecting bar 23 at its other end having a pivotal connection to bar 26 between the ends thereof.

The bar 26 extends upwardly to a chain operating mechanism located adjacent but underneath the upper run of the endless chain 17. Such chain operating mechanism comprises two spaced pairs of upper and lower horizontal guide bars 27 connected together at their ends which serve as guides and tracks for rollers on a carriage 28, a short link 29 connecting the upper end of the bar 26 with an end of the carriage. Dogs 30, pivotally mounted on the carriage, are acted upon by a tension spring 31 so as to normally occupy a vertical position. When in such position, in one movement of the carriage over the tracks, to the left in Figs. 8 and 9, they engage plates 17a extending laterally from the underside of the chain 17. This moves the chain the distance that the carriage is moved in such direction of its movement. On the return movement of the carriage the dog 30 will be swung downwardly toward the dash line position shown in Fig. 9 and pass underneath the chain and the plates 17a.

Adjacent the end of the tracks toward which the carriage moves in its chain actuating movement are levers 32, which are pivotally mounted between their ends and are normally held in a lowered position by a tension spring 32a. There are two of these levers and two of the dogs 30 which traverse longitudinal slots in a cover plate 33 located over and secured to the track and guiding frame. When the carriage approaches the end of its chain actuating movement it engages the lower portions of the levers 32 and turns them to a vertical position shown in dash lines in Fig. 9 to interpose in the path of movement of the plates 17a. This positively stops the chain at a predetermined position substantially when the carriage has reached its extreme position of movement, checking any tendency for the momentum of the chain and parts connected therewith to carry the chains beyond desired position and preventing overmovement. As soon as the carriage starts on its back movement the

4
levers 32 are released and returned to their lowered position.

Two chain wheels 34, with an endless conveying chain 35 around them, are mounted on shafts 36 adjacent opposite ends of the machine. Such chain and carrying wheels therefor have horizontal upper and lower runs and are located back of the chains 12 (Fig. 3). On the chain 35 a plurality of plates 37 are permanently secured at equal spaced distances from each other. Each of the plates 37 at its front side has a projection to which a spring receiving member 38 is pivotally connected by means of a lug 39 fixed thereto (Fig. 4) one for each of the forward projections of the plates 37. The spring receiving members are of flat metal of channel cross section, one end of which is closed, as shown at 38a, and the web of each channel adjacent such closed end of the member is cut away to provide an opening 40.

The chain 35 is actuated in periodic step by step movements in unison with the chain 17 by means of a bar 41, also fixed at its lower end to the rock shaft 25, extending upwardly to an identical mechanism for moving the chain as that shown in Figs. 8 and 9 with respect to the chain 17. The spring holding members normally extend downwardly from the lower run of the chain 35 (Fig. 2). In such vertical position when the lower run of the chain reaches an end of the machine, the right-hand end shown in Fig. 2, members 38 ride against and upon a guide and cam bar 42 of curved form at the end of the machine and thence extending for a distance longitudinally of the machine. The spring receiving members 38 are progressively swung from their depending vertical position to a horizontal position thence tilted upwardly toward a vertical position. When they are in an intermediate or inclined position adjacent the end of the machine they receive the coiled cushion springs 43, one in each spring receiving member 38. Our prior application, Ser. No. 103,152, filed July 5, 1949, discloses the spring selecting and feeding machine which delivers the selected springs, three in number in practice, one to each of three consecutive spring receiving members 38. Such springs 43 are delivered to the receiving member 38 while such members are at rest or between the periodic movements of the chain 35. On succeeding movements of the chain the spring holding members 38 with the springs 43 therein are turned to vertical position by engagement with the cam guide 42 and come against a vertical plate 44 (Fig. 4). While against such plate 44 they cannot be turned to horizontal position, because the pivots connecting the lugs 39 to associated plates 37 are located above the closed lower ends 38a of such spring receiving members opposite the vertical plate 44.

60 A spring loading mechanism, similar to that shown in the prior filed application, Ser. No. 791,712, filed December 15, 1947, is incorporated in the machine, having some changes in structure and improvements. Such spring loading mechanism is located between the ends of the machine at what may be termed the loading station which is at the front of the rear extension of the machine frame. It includes a vertical guide frame having at each side pairs of vertical spaced bars 45 connected at their upper ends and at their lower ends reaching to the table section 11 and secured thereto, the bars 45 adjacent their lower ends having integral connection with or connected to a slotted widened section 45a.

65 A vertical spring plunger carrying frame is

slidably mounted for vertical movements between the sides having the spaced bars 45, having an upper horizontal cross bar 46, spaced vertical sides 47, on which rollers are mounted to extend between the bars 45, and a lower cross bar 48. Vertical rods 49 extend downwardly from the upper cross member 46, each rod being secured to the cross member and equipped with a presser head 50 at its lower end of a size and shape to be received within a spring receiving member 58. There are three of these rods and three of the spring pressers in the machine as used.

During the movements of the chain the plungers are elevated so that the heads 50 are above the upper ends of the spring receiving members 58 (Fig. 2). At the rest or dull periods between successive movements of the chain, the frame carrying the spring pressers is moved downwardly, as hereafter described, and each of the coiled compression springs 43 is compressed in the direction of its axial length, the springs being compressed so that their upper ends are below the upper side of the opening 40 and are also below the lower edge of the plate 44 which is spaced a distance above the table member at 11. In Fig. 4 the compression of the spring has not reached its extreme of compression, the heads 50 at their lowermost limits reaching substantially the position shown in Fig. 5.

On the lower cross bar 48 of the vertical movable frame, rods 51, three in number are permanently secured and extend downwardly therefrom, at the lower end of each of which a cam plate 52 is permanently secured, the lower outer corner portion of which is cut away to provide an inclined edge or side. Three arms 53 are permanently connected at their forward ends to a rock shaft 54 mounted on its ends between the spaced lower end portions 45a of the fixed carrying guiding frame on which the spring presser frame is mounted. Said arms extend rearwardly and carry rollers at their free ends which, when the rods 51 and plates 52 are in an upper position, are in the path of movement of the inclined lower edge of the plates 52. Other arms 55 are permanently secured to the rock shaft 54, extending generally downward therefrom, and at their lower ends are connected to a horizontal rod 56, the ends of which are disposed in generally horizontal slots 57 in the parts 45a. Also on the rods 56 flat sheet metal members 58 are pivotally mounted, each at its front end having an upturned lip 58a. The fabric bags 59 which are to receive the springs 43 have lower sides, the edges of which extend farther back than the edges of their upper sides. Springs 60 surround the rod 56 and have end portions bearing against the shaft 54 and the upper sides of the members 58 tend to depress the front lip portions 58a of the members 58 so that such members bear against the upper side of the lower sides of the fabric bags 59 at a point back of the rear edges of the upper sides thereof (Fig. 4). When the spring compressors are moved downwardly, the inclined lower edge portions of the plates 52 ride against the rollers and rock the rock shaft 54 counter-clockwise (Figs. 4 and 5), moving the rod 56 and the members 58 thereon outwardly in a forward direction to bring the lips 58a and adjacent portions of plates 58 under the upper sides of the fabric pockets and the lowermost end portions of the plates 52 press against members 58 back of their pivotal mounting, whereupon the upper sides of the fabric bags 59 are lifted above the

lower sides thus opening the pockets, three in each bag 59, for reception of the compressed springs 43 therein.

Loading the springs is by means of spring pushing or loading members, each including a rod 61 with a head 62 at its front end. Such rods are adapted to pass through the openings 49 and the space between the lower edge of the plate 44 and the table 11, the heads 62 engaging the compressed springs 43 and moving them over the table 11 and underneath the members 58, the compressed springs being forced into the open ends of the fabric pockets.

In practice and as the disclosure shows, the pockets are supplied each with a spring 43 in series of three, thus there are three of the rods 61 each with its head 62 thereon. The number of pockets in a bag 59 and of compressor and loading rods and heads may be varied.

The mechanism for operating the spring compressing plungers and the spring loading rods and heads is best shown in Figs. 1, 3 and 7. Beveled gearing 63 on the shaft 21 and on a shaft 64 (Fig. 1) at right angles to it connect the two shafts for driving the shaft 64, which is located toward the lower portion of the machine and at the forward portion of the rear extension to the machine frame. Three cams are fixed to the shaft 64. Two of such cams at 65 are of identical form and construction and may be designated as side cams spaced apart from each other. Between them is a third cam 66. The cams 65 each actuates a bar 67, rollers on said bars between the ends thereof entering the grooves of the cams, shown in Fig. 3. At their upper forward ends the bars 67 are pivotally connected to generally vertical rods 68 which at their upper ends are connected with the sides 47 of the spring compressor frame. At their opposite ends bars 67 are fixed to a rock shaft 70, mounted at its ends in bearings secured to the lower horizontal frame members 8 of the machine frame. Center cam 66 operates arm 69 mounted on the shaft 70.

Bars 71 are also mounted on the rock shaft 70 at their lower ends, extending upwardly to a carrying and guiding frame for the spring loading rods 61. The bars 71 are fixed to the rock shaft 70, having sleeves 72 at their lower ends (Fig. 7) through which the shaft passes. The arm 69 also has a like sleeve 72 through which shaft 70 passes also fixed to the shaft so that the center cam 66 operating the arm 69 rocks the shaft 70 and the rock shaft 70 swings the arms 71 back and forth. The sleeves 72 at the ends of the bars 67 are loose upon the shaft 70. Links 74 connect the upper ends of bars 71 with a carriage of rectangular form at 75 (Fig. 1), which is mounted on rollers extending from the sides of the carriage to pass between horizontal carrying and guide bars 76 spaced from each other and mounted on the frame of the machine and which are stationary with respect to such frame. The forward ends of the bar 76 are connected by a cross bar 77 through which the rods 61 pass (Fig. 5). Such rods 61 at their rear ends are permanently secured to the front bar of the frame 75. The swinging movement of the bars 71 back and forth reciprocates the frame 75 so as to move the spring loading rods 61 in a forward direction to load the fabric pockets and return the frame and connected rods 61 to the rear after such loading is accomplished.

It will be noted from the form of the grooves in the cams 65 and 66, that for approximately one-half of the rotation of the shaft 64 there is

no movement of the rock shaft 70 and of the bars 67 and 71. Thus the spring loading bars 61 and the frame 75 to which the bars are connected are at rest during substantially one-half of such rotation of shaft 64 and a complete reciprocation of the rods 61 takes place during the other half of said movement. Likewise, the vertical movable carriage to which the spring compressing rams are attached is likewise at rest during substantially one-half of each rotation of the shaft 64 and a downward followed by the upward movement of the spring compressing plungers is completed during the remaining one-half of such rotation. The timing of the movements is such that when the springs are completely compressed, the forward movement of the frame 75 and rods 61 occurs and the springs are forced into the fabric pockets in the bags 59, and the return of the spring compressing plungers to upper position and of the spring loading rods 61 and their heads 62 to their rear position occurring nearly simultaneously. Also, such compressing of the springs and their loading into the pockets takes place while the chain 35 and the spring receiving members 38 attached thereto are at rest.

A still additional chain wheel 78 is mounted on the shaft 15 at the end of the machine nearest the loading station which, through a chain 79 and a suitable wheel drives a horizontal shaft 80 to which a roller 81 is affixed. The roller 81, in the main, is below the table 9. Spaced horizontally from it is a second roller 85 in the same plane. Around the rollers an endless belt 82 passes, the upper run of which rides over the upper side of the table 9 and has its upper side flush with the upper side of the table. Vertical supports 83 and 84 connected with the main frame (Fig. 2) support the shaft on which the rollers 81 are mounted and also extend upwardly above the table 9. A second endless belt 86 over and spaced from the lower belt 82 passes around rollers 85 carried by horizontal shafts 87 between the upper ends of the vertical supports 83 and 84. A short vertical shaft 88 (Fig. 6) is between the forward ends of the shafts 80 and 87 and through the beveled gearing 89 connects the shafts together, so that the upper run of the lower belt and the lower run of the upper belt move in the same direction toward the adjacent end of the machine. The gearing connections between shafts 80, 88 and 87 is covered by a sheet metal housing 90 (Fig. 6).

When the pockets of the bags 59 receive the compressed springs 43 therein, such pockets have been moved to a position between the adjacent horizontal runs of the belts 82 and 86. Each fabric bag 59 is divided into three side by side pockets each of which simultaneously receives a compressed spring 43 therein at the loading stage. Where the springs are forced into the three pockets they are held against extension by the pressure of the upper belt 86 stopping expansion in a vertical direction and by the lower belt 82 and the table 9 below it which prevents extension in a downward direction. Such extension of the springs cannot take place until the spring loaded fabric pockets have passed beyond the belt. The belts 82 and 86 are actuated in periodic step by step movements with intervals of rest between such movements and are stationary when the loading of the springs takes place. When they leave the belts they go to other mechanisms, no part of the present invention and not shown herein, for closing the open ends of the pockets and with the springs extending and turned at

right angles to the position which they occupy in Fig. 5, so as to lie lengthwise of the pockets in which they are received.

With a machine constructed as described, a very rapid quantity production is attained in the matter of filling the pockets with the desired springs, which springs may be of varying tension as disclosed in our prior application above referred to, the selection of which for delivery to the machine of the present invention is disclosed in said recently filed application. With the delivery of each plurality of springs one to each of the spring receiving members 38, with such members and the chain to which they are attached at rest, there follows a succeeding step of movement of the chain 35 and the attached spring receiving members toward the loading stage. The next succeeding three spring receiving members 38 receives the next three springs when the chain conveyor 35 again stops in movement. The compression of the springs and the loading thereof as previously described is properly timed with the movement of the several conveyor chains, so that at the loading stage when the loading takes place the mechanism is at rest, except for the downward movement of the spring compressing rams followed by their return to upper position and the forward movement of the spring loading rods 61 and heads 62 followed by their return to their initial rear position, which occurs before the next succeeding movement of the conveyor chain 35 and attached spring receiving members 38 takes place. The belts 82 and 86 are likewise driven in unison with the conveying chain 35. Very rapid loading of the springs is attained, greatly lessening hand labor previously used in many of the operations between the selecting of the springs which are to be used, and a completion of the final loading of the springs into their fabric receiving pockets.

The invention is defined in the appended claims and is to be considered comprehensive of all forms of structure coming within their scope.

We claim:

1. In a structure as described, a horizontal table, an endless horizontal conveyor having an upper run passing over said table, said conveyor at spaced distances in the length thereof having outwardly projecting pins, a second horizontal conveyor, a plurality of elongated spring receiving members hingedly connected to said second conveyor at equally spaced distances in the length thereof, said spring receiving members depending vertically from the lower run of their conveyor and occupying generally horizontal positions in changing from the lower to the upper runs of the conveyor in the movements thereof, camming guide means over which the spring receiving members of the upper run of the conveyor ride for changing said spring receiving members from horizontal through inclined positions to vertical positions with the progress of the upper run of the conveyor, said spring receiving members being adapted to receive individual coiled compression springs therein while at an inclined position, said spring receiving members being open at their outer ends, vertically movable spring compressing members mounted between the ends of the said second conveyor and movable to a position above the upper ends of said spring receiving members, means for driving both of said conveyors simultaneously in step by step periodic movements with rest intervals between movements, means for driving the spring compressors downwardly

to compress the springs followed by an upward movement of said spring compressors, horizontally located spring loading members movably mounted for reciprocation in a horizontal plane, said spring receiving members adjacent their lower ends having openings for the passage of said spring loading members, and means for moving said spring loading members horizontally to force the compressed springs from the spring receiving members into the open ends of said bag pockets, followed by a return backward movement of said spring loading members to initial position while said conveyors are at rest between movements thereof.

2. A structure as defined in claim 1, and endless belts horizontally located one over the other with the upper and lower runs of said belts spaced from each other and between which bags having springs receiving pockets therein are moved in succession with succeeding movements of said conveyors, and between which said bags are located upon loading compressed springs thereinto, said belts holding the springs compressed between their adjacent upper and lower horizontal runs, and means for driving said belts for movement of the adjacent upper and lower runs thereof in the same direction as the upper runs of said conveyors, in equal amounts and simultaneously therewith.

3. In the machine of the class described, an endless conveyor chain, a plurality of plates secured to said chain at equally spaced distances in the length thereof, a spring receiving member hingedly connected to each plate whereby the members may be swung from horizontal to vertical positions and vice versa said spring receiving members being of channel form in cross section and closed at one end, means for moving the chains in periodic step by step movements for predetermined distances in the length thereof with intervals of time between movements during which the chain is at rest, means for swinging said spring receiving members from a downwardly depending position at the lower run of the chain to an upwardly extending vertical position in the upper run of the chain with the open ends of the spring receiving members at the upper ends thereof, an elongated vertical member along which the open sides of said spring receiving member at the upper run of the chain move at and prior to coming to said loading station, means for compressing a predetermined number of said springs in said spring receiving members at said loading station while the chain is at rest, means for horizontally moving the compressed springs at the loading station into the open ends of fabric pockets adapted to receive them, and means for operating said spring moving means while the chain and the spring receiving members are at rest and immediately after the springs at the loading station have been compressed.

4. A structure as defined in claim 3, and a horizontal table over which said compressed springs are moved, a conveyor at a longitudinal edge of the table, fabric bag attaching means carried by the table for releasably securing bags, open at one end to said conveyor with the open ends presented to receive the compressed springs, said bags having longitudinal pockets extending from the open ends of the bags to the other ends thereof, and means to drive said conveyor simultaneously and in equal amounts with said endless chain.

5. In a machine as described a horizontal

table, a conveyor movable lengthwise of the table, pins extending upwardly from the conveyor for attachment of bags having spring receiving pockets open at one end, said bags being movable over the table on movement of the conveyor means for moving said conveyor a predetermined distance in the direction of its length at spaced intervals of time between movements, a loading station between the ends of said conveyor, means for compressing coiled cushion springs in the direction of their length at the loading station, means for moving and loading the compressed springs into the pockets at their open ends combined with means for operating said spring compressing and spring loading means during the times between the movements of conveyor, and horizontal conveying means at the loading station to which the bags in succession are brought with the movements of the conveyor, movable pressure means located above said conveying means for holding the springs compressed in the bags after loading therein, and means for moving said conveying means and pressure means simultaneously with said conveyor.

6. In a machine of the class described, a support having a horizontal table, an endless conveyor having an upper run located above the table, connectors on said conveyor in the length thereof and extending outwardly therefrom to which bags having an open end and having spring receiving pockets to receive springs may be detachably connected to move with said conveyor over the table, means for periodically driving said conveyor with intervals of rest between movements thereof, each movement being for a predetermined distance, means for loading the pockets in said bags with compressed coiled cushion springs at the open ends thereof at a predetermined position in the length on the table and during periods when the conveyor is at rest between movements thereof, and a second horizontal conveyor, spring receiving members secured to said conveyor and movable therewith and connected therewith at equally spaced distances in the length thereof, each of said spring receiving members being adapted to receive a coiled cushion spring therein to be carried thereby, spring compressing means at a predetermined position in the length of the second conveyor for compressing the springs in said receiving members in the direction of their axial length, means for mounting said spring compressing means for vertical reciprocating movements to compress the springs on the downward movement thereof, means for driving said spring compressors during the times that said second conveyor is at rest between movements thereof, and means mounted for horizontal reciprocation located at the back of the compressed springs and movable in a forward direction to engage the compressed springs and move them into the pockets of said bags, combined with means for reciprocating said spring moving means timed to occur while the conveyors are at rest and with the springs compressed.

7. A machine of the class described comprising, a loading station, means for carrying open-ended formed bags to and beyond said loading station, means at said loading station for inserting a coiled compression spring compressed in the direction of its axis into a bag with said axis transverse to the sides of the bag, pressure means located closely adjacent said loading station and extending away therefrom in the direction of

movement of the bag engaging opposite sides of the bag opposite ther compressed spring therein, acting to hold said spring compressed in the bag beyond the loading station for further operation on the bag, and a second conveyor moving synchronously with said bag conveyor to said loading station, a plurality of individual spring receivers attached to said second conveyor and brought successively to said loading station, means for compressing the spring within each receiver at said loading station and means for inserting said compressed spring into a bag through its open end.

8. A machine of the class described comprising, a loading station, means for successively conveying open ended bags to said loading station, a spring conveyor moving to said loading station, a plurality of individual spring receivers on said spring conveyor each movable successively to said loading station, means for compressing a spring within a receiver means for inserting said compressed spring into a bag through its open end at said loading station, each of said spring receivers having an open side through which springs are inserted into the receivers and a plate at said loading station adjacent to which said open side of a receiver is moved, said plate acting to close said open side.

9. The elements of claim 8 combined with means located ahead of said loading station in the direction of movement of the conveyor acting to move said spring receivers into oblique positions with their open sides inclined upward, and means for moving said receivers into position with their open sides vertical at said loading station.

10. The elements of claim 8 in which each of said receivers is channel-shaped having an open side, an open upper end and a closed lower end.

WILLIAM K. McINERNEY.
JAMES M. McINERNEY.
